(57) **CLAIM**

The ornamental design for a mask for respirator, as shown and described.

DESCRIPTION

FIG. 1 is a perspective view of a mask for respirator showing our new design;

FIG. 2 is a front elevational view thereof;

FIG. 3 is a rear elevational view thereof;

FIG. 4 is a right side elevational view thereof; the left side elevational view is a mirror image of the right side elevational view;

FIG. 5 is a top plan view thereof; and,

FIG. 6 is a bottom plan view thereof.

The broken lines shown in FIGS. 1 to 6 are for illustrative purposes only and form no part of the claimed design.
